UNITED STATES PATENT OFFICE

95,313

DESIGN FOR A STOVE

Garvin M. Brown, Indianapolis, Ind.

Application February 4, 1935, Serial No. 55,224

Term of patent 7 years

To all whom it may concern:

Be it known that I, Garvin M. Brown, a citizen of the United States, residing at Indianapolis, in the county of Marion and State of Indiana, have invented a new, original, and ornamental Design for Stove, of which the following is a specification, reference being had to the accompanying drawing, forming a part thereof.

The figure is a perspective view of the stove, showing my new design, the opposite side walls being duplicates in design, and rear wall being substantially plain.

I claim:

The ornamental design for a stove, as shown and described.

GARVIN M. BROWN.
